UNITED STATES PATENT OFFICE.

CHRISTOPHER C. GALLERY, OF WEST COATESVILLE, PENNSYLVANIA.

PIPE CLAMP.

Application filed October 1, 1925. Serial No. 59,861.

This invention relates to an improved device which may be conveniently referred to as a pipe clamp, the same being adapted to be used in connection with the jaws of a vise or equivalent structure for firmly holding a section of pipe while the same is being threaded, either internally or externally.

Briefly, the invention has reference to a clamp which is made up of a pair of hinged-
10 ly connected half-sections between the op-
posed faces of which the pipe is firmly held,
each half section being composed of detach-
ably connected substantially semi-circular
grips nested together in a novel manner.
15 Considered from a different aspect, the
semi-circular grips may be said to be halves
of split bushing, each bushing being of a
predetermined size so that one or more of
the bushings may be removed to accommo-
20 date pipes of smaller or greater diameter, as
the case may be.

My principal aim is to generally improve upon inventions of this class by providing one of comparative simplicity and dura-
25 bility which is constructed to assure a firm and efficient grip on the pipe in a manner to prevent undue marring of the surface, and possible crushing from any powerful pressure from the jaws of the vise.

30 Other features and advantages of the invention will become apparent from the following description and drawing.

In the accompanying drawing forming a part of this application, and in which like numerals are employed to designate like parts throughout the same.

Figure 1 is an end elevation of a pipe clamp constructed in accordance with the present invention, showing the manner in
40 which it cooperates with a section of pipe and with the jaws of a vise.

Figure 2 is a top plan view with a portion broken away and shown in section.

Figure 3 is a central section through the
45 clamp on the pipe.

Figure 4 is a perspective view of one of the details.

Referring to the drawings in detail the reference character A designates the body portion of one of the jaws of a conventional pipe holding vise or its equivalent, and B designates the face plate thereof.

The improved clamp, which is adapted to be placed between the plates B comprises,
55 as before intimated, a pair of duplicate half-sections 1 hingedly connected together

as at 2. Each half section is variable in form, and is made up of an outer comparatively hard metal segment 3 forming one-half of the outer casing. Confined within 60 this sectional casing are what may be referred to as longitudinally split bushings, each of which is removable to permit the central opening of the clamp to be varied in diameter to accommodate pipes of different 65 diameters.

Each bushing is actually made up of duplicate semi-circular halves 4 gradually decreasing in size toward the center. In fact the innermost halves may be reduced 70 in thickness. Moreover, as shown in Figure 4 each half is formed with longitudinally spaced holes 5 through which lugs 6 on an adjacent section pass. In addition, notches 7 are formed in the upper ends of the halves 75 to facilitate separation.

It is yet to be pointed out that appropriate spring latches 8 may be connected with one of the half sections 1 to coact with keepers 9 in the other half sections to hold 80 the two half sections together when the clamp is removed from the latch.

From the foregoing description it is obvious that the half sections of the clamp are swung apart and that the pipe 10 is placed 85 therebetween, after which the clamp and the pipe are placed between the face plates of the jaws, and the jaws piped in the usual manner, thereby obtaining an indirect grip through the medium of the clamp on the 90 pipe. The fact that the clamp is cylindrical in form and comparatively long, affords a grip having considerable area, and thereby guarding against crushing and injury of the pipe. In this connection I wish to call attention to the fact that the outer casing formed by the halves 3 is of comparatively 95 hard metal, while the interconnected or nested bushing forming sections are of a more or less malleable metal.

The gist of the invention resides in the particular construction, arrangement of parts wherein sectional bushings are confined within a sectional casing, the sections of the bushings being nested together and held in 105 assembled relation by projections fitting into complementary openings so that by using a suitable instrument, the sections may be pried apart to adjust the central opening to any desired diameter to fit different 110 diameters of pipes.

The invention will be clear to those skilled

in the art to which it relates, after considering the description in connection with the drawings. Therefore, a more lengthy description is thought unnecessary.

5 While the preferred embodiment of the invention has been shown and described, it is to be understood that minor changes coming within the field of invention claimed may be resorted to if desired.

10 Having thus described the invention, what I claim as new is:—

A pipe and tube holding device of the class described comprising an outer casing formed of integrally connected halves, means 15 for connecting said halves together, and a

plurality of bushings arranged in said casing, each bushing being composed of a pair of half-sections of symmetrical configuration, and co-acting means between the adjacent sections of the respective bushings for maintaining said sections in nested relation, whereby to adapt said device for clamping pipes of various diameters, said co-acting means comprising lugs on the outer faces of said sections fitting into correspondingly 25 shaped holes on the inner faces of the cooperating sections.

In testimony whereof I affix my signature.

CHRISTOPHER C. CALLERY.
